William N. Chamberlain

United States Patent Office.

WILLIAM N. CHAMBERLAIN, OF VAN BUREN, MICHIGAN.

Letters Patent No. 96,307, dated November 2, 1869.

IMPROVEMENT IN PUMPS.

The Schedule referred to in these Letters Patent and making part of the same.

To all whom it may concern:

Be it known that I, WILLIAM N. CHAMBERLAIN, of Van Buren, Michigan, have invented an Improved Pump; and I do hereby declare the following is a full, and exact description thereof, reference being had to the accompanying drawings, and to the letters thereon.

Figure 1 is a side elevation of my pump.

Figure 2 is a section, showing the construction and arrangement of the several parts thereof.

My object is to make a cheap and an efficient pump; and my invention consists chiefly in the arrangement and construction of the parts of my pump, as will be apparent in the description.

In fig. 1, A is a common wood pipe, such as is made for chain-pumps, and is of any suitable length, to which a short piece of pipe, A', is joined and secured by the frame-piece F, and B is a cylinder surrounding the lower end of the wood pipe, which is made round, and to fit at A" the inside of the cylinder.

The cylinder I make preferably of galvanized iron, and a packing of leather or other suitable material is placed between the wood pipe and cylinder.

On the sides of the cylinder are two wings, C' and C", to which two wood rods, D' and D", are attached. The two rods are connected at the top of the well with

a pump-handle; and thus the action is to raise the cylinder over and up on the wood pipe, thus making a lifting force-pump.

There are valves, one, the upper, at the junction of the wood pipes A and A'; and the other at the bottom of the cylinder.

In fig. 2, the same letters show the same parts, E being the upper, and G the lower valve, and H the packing between the piston end of the wood pipe and the metallic cylinder.

The advantages and uses of my invention are apparent to those skilled in the art to which it appertains.

Claims.

1. The pipe A, with the piece or part A' at its lower end, and holding the valve E on its top, in combination with the cylinder B, and its valve G, substantially as and for the purposes set forth.

2. The combined whole, made by the pipes A A', cylinder B, valves E and G, frame F F', and lifting-rods D D', arranged substantially as set forth.

WILLIAM N. CHAMBERLAIN.
